UNITED STATES PATENT OFFICE

159,896

RADIO CABINET OR SIMILAR ARTICLE

Edwin Durst, New York, N. Y.

Application January 15, 1949, Serial No. 242

Term of patent 14 years

(Cl. D56—4)

To all whom it may concern:

Be it known that Edwin Durst, a citizen of the United States and resident of New York city, in the county of New York, State of New York, has invented a new, original, and ornamental Design for a Radio Cabinet or Similar Article, of which the following is a specification, reference being had to the accompanying drawing, forming part thereof, in which the figure is a perspective view of a radio cabinet, or similar article, showing my new design.

The rear of the cabinet is of conventional design.

I claim:

The ornamental design for a radio cabinet or similar article, as shown and described.

EDWIN DURST.
